Patented July 14, 1914.

UNITED STATES PATENT OFFICE.

JOHN JOHNSON, OF STILES, WISCONSIN.

LOADING AND UNLOADING DEVICE.

1,103,209.

Specification of Letters Patent. Patented July 14, 1914.

Application filed October 22, 1913. Serial No. 796,695.

To all whom it may concern:

Be it known that I, JOHN JOHNSON, citizen of the United States, residing at Stiles, in the county of Oconto and State of Wisconsin, have invented certain new and useful Improvements in Loading and Unloading Devices, of which the following is a specification, reference being had to the accompanying drawings.

10 This invention relates to loading and unloading apparatus and has for its primary object to provide a simple, efficient and reliable means for loading hay, fodder or other materials into a barn or conveying the same to the exterior of the barn and loading it upon a wagon or other vehicle.

20 My invention has for another and more specific object the provision of a double pulley, the pulley members being of relatively different diameters, a rope or cable fixed at one of its ends to the larger pulley and provided at its other end with a fork or carrier, supporting rollers for said cable, and a weighted cable fastened at one end to 25 the smaller pulley.

30 My invention has for another of its objects to produce a device of the above character which is extremely simple in construction, highly efficient and reliable in practical use and may be manufactured and installed at comparatively small cost.

35 With the above and other objects in view as will become apparent as the description proceeds, the invention consists in certain constructions, combinations and arrangements of the parts that I shall hereinafter fully describe and claim.

40 For a full understanding of the invention, reference is to be had to the following description and accompanying drawings, in which—

45 Figure 1 is a side elevation of my improved loading and unloading device arranged in a barn, the fork or carrier being shown pulled back from the barn entrance in dotted lines; Fig. 2 is a similar view but illustrating the trip device arranged centrally of the barn and above the entrance thereto, the fork or carrier being adapted to 50 be pulled in either direction from the trip as shown in dotted lines; Fig. 3 is a section taken on the line 3—3 of Fig. 1. Fig. 4 is an enlarged detail view of the hay fork or carrier.

55 Referring in detail to the drawings, 5 designates a pulley of large diameter and 6

indicates a pulley of comparatively small diameter which is rigidly secured upon one side of the larger pulley by means of a plurality of bolts 7. In the peripheral groove 60 of the large pulley, 5 one end of a wire, rope or cable 8 is secured. This cable extends over and is supported by a plurality of rollers 9 mounted in any preferred manner upon a beam or other part of the barn 65 structure. To the other end of the cable 8, the fork or carrier 10 is attached.

A suitable trip device generally indicated by the numeral 11 is arranged at the entrance to the barn and is adapted to coöperate with certain parts of the fork or carrier 10 to release the bundle of hay, fodder or other material carried thereby. In Fig. 4 of the drawings, I have illustrated a very common form of fork or carrier, wherein 16 75 indicates the arms of the fork in the extremities of which the grapple members 17 are pivotally mounted intermediate of their ends. Adjacent the inner ends of the fork arms 16, bars 18 are fulcrumed adjacent 80 their outer ends as indicated at 19, the inner ends of said bars having a sliding pivotal connection with the vertically disposed rod 20. The corresponding ends of the grapple members 17 and the bars 18 are connected 85 by link rods 21. From this construction, it will be apparent that when the grapple members 17 are in the position shown in Fig. 4, the hay bundle will be securely held between the arms of the fork. These members are released from engagement with the bundle by contact of the vertically disposed rod 20 with the trip element 11 above referred to, it being understood that said rod is forced downwardly to move the bars 18 90 and through the medium of the links 21 thus throw the inwardly extending ends of the grapple members 17 outwardly. It will be understood, however, that the present invention is not limited to this specific type 95 100 of grapple and trip therefor, as various other equivalent devices for holding and releasing the hay bale may be employed. A pull rope 12 is also attached at one of its ends to the carrier 10, whereby said carrier 105 may be pulled into the barn when the same has been supplied with its load. To the periphery of the smaller pulley 6, one end of a wire, rope or cable 13 is attached. This cable also extends over a suitable guide 110 roller 14 and is provided upon its other end with a weight 15.

It will be obvious from the above description that when the fork or carrier is pulled into the barn, as shown in dotted lines in Fig. 1, the cable is unwound from the pulley 5, thereby rotating said pulley and consequently the smaller pulley 6. Upon this latter pulley, the cable 13 is wound, thereby raising the weight 15. After the fork or carrier 10 has been supplied with a load or bundle of fodder, the operator releases the rope 12 so that the weight 15 will descend, thereby rotating the pulley 5 and winding the cable 8 thereon whereupon the carrier 10 will be moved outwardly to the barn entrance and into engagement with the trip 11. By means of this trip the bundle is automatically released from the carrier so that it will drop into a vehicle arranged beneath the same.

In Fig. 2, I have shown a slightly different method of mounting the apparatus, wherein the trip device is arranged above the door opening provided in the side wall of a long barn or warehouse. The double pulley is mounted in one end of the barn and as shown in full lines, the weight on the cable attached to the small pulley 6 normally holds the fork or carrier above the barn entrance. The operator may pull the carrier by means of the rope connected thereto to either the right or left hand side of the barn entrance as occasion may demand to remove the bundles or bales stored therein. In either instance, the descent of the weight 15 will act to wind the cable 8 upon the pulley 5 and return the carrier to its normal position for engagement by the trip device whereupon the bundle will be released.

From the foregoing, it is thought that the construction and manner of operation of my invention will be clearly and fully understood. The weight acts to immediately return the bundle to its normal position, when the pull cord is released, and it will be obvious that by means of the apparatus,

the loading or unloading of materials may be greatly facilitated. Owing to the extreme simplicity of my invention, it will be obvious that the same may be produced at very small cost and readily installed in the barn or warehouse.

While I have shown and described the preferred form and arrangements of the several parts of the device, it will be obvious that the invention is susceptible of many minor modifications therein and I therefore reserve the right to resort to all such legitimate changes as may fairly fall within the spirit and scope of the invention, as claimed.

Having thus described the invention, what is claimed is:

In an apparatus of the character described, a rotatably mounted pulley, a second pulley of relatively smaller diameter fixed upon one side of said first pulley, a cable secured at one end to the periphery of the first pulley, a carrier attached to the other end of said cable, supporting rollers for said cable, a second cable secured at one of its ends to the periphery of the smaller pulley, a guide roller for said latter cable, a weight secured to the other end of said cable, said cable extending to the smaller pulley from an opposite direction with relation to the connection of the carrier cable to the first named pulley, and a pull cord attached to the carrier whereby the carrier may be moved to position to be loaded and the pulleys rotated to wind the latter cable upon the smaller pulley and elevate the weight attached thereto, the descent of said weight reversing the rotation of the pulleys and winding the first cable upon the larger pulley when the pull cord is released to return the carrier to its normal position.

In testimony whereof I hereunto affix my signature in the presence of two witnesses.

JOHN JOHNSON.

Witnesses:

JOS. BIRKENMEIER,
ARTHUR A. Foss.
